TRAFFIC SIGNAL

Myron F. Pettengill, Hendersonville, N. C., assignor to
General Electric Company, a corporation of New York

Application December 22, 1955, Serial No. 39,447

Term of patent 14 years

(Cl. D72—1)

Fig. 1

Fig. 2

Fig. 1 is a side elevational view of a traffic signal showing my new design; and

Fig. 2 is a front elevational view thereof.

I claim:

The ornamental design for a traffic signal, as shown.
